US00D821589S

(12) **United States Design Patent** (10) Patent No.: **US D821,589 S**
(45) Date of Patent: **** Jun. 26, 2018**

(54) HEEL ADHESIVE PATCH	D278,363 S	4/1985	Schenkel et al.
(71) Applicant: EuroMed, Inc. , Orangeburg, NY (US)	4,538,603 A	9/1985	Pawelchak et al.
(72) Inventors: Ljiljana Sakotic , Greenwood Lake, NY (US); Matthew J. Clemente , Glen Rock, NJ (US); Nohora Cardenas , New Milford, NJ (US)	4,564,010 A	1/1986	Coughlan et al.
(73) Assignee: EuroMed, Inc. , Orangeburg, NY (US)	4,649,909 A	3/1987	Thompson
(**) Term: 15 Years	4,743,499 A	5/1988	Volke
(21) Appl. No.: 29/589,432	4,917,112 A	4/1990	Kalt
(22) Filed: Dec. 30, 2016	5,056,510 A	10/1991	Gilman
(51) LOC (11) Cl. 24-02	5,109,874 A	5/1992	Bellingham et al.
(52) U.S. Cl. USPC D24/189	D340,114 S	10/1993	Arginsky
(58) Field of Classification Search	5,266,371 A	11/1993	Sugii et al.
USPC	5,431,911 A	7/1995	Reynolds

(57) CLAIM

The ornamental design for a heel adhesive patch, as shown and described.

DESCRIPTION

FIG. 1 is a top perspective view of a heel adhesive patch showing our new design, with removable flaps in a position to be removed.

FIG. 2 is a top view of the heel adhesive patch showing our new design, with removable flaps in a position to be removed.

FIG. 3 is a bottom view of the heel adhesive patch of our new design.

FIG. 4 is a front side view of the heel adhesive patch showing our new design, with removable flaps in a position to be removed.

FIG. 5 is a back side view of the heel adhesive patch showing our new design, with removable flaps in a position to be removed.

FIG. 6 is a right side view of the heel adhesive patch showing our new design, with removable flaps in a position to be removed.

FIG. 7 is a left side view of the heel adhesive patch showing our new design, with removable flaps in a position to be removed.

FIG. 8 is a top perspective view of a heel adhesive patch showing our new design, with removable flaps on one side in a position to be removed.

FIG. 9 is a top view of the heel adhesive patch showing our new design, with removable flaps on one side in a position to be removed.

FIG. 10 is a right side view of the heel adhesive patch showing our new design, with removable flaps on one side in a position to be removed; and,

FIG. 11 is a left side view of the heel adhesive patch showing our new design, with removable flaps on one side in a position to be removed.

The broken lines shown in FIGS. 1-5 and FIGS. 8-9 illustrate portions of the heel adhesive patch that form no part of the claimed design.
